US0D1031333S

(12) United States Design Patent (10) Patent No.: US D1,031,333 S
(45) Date of Patent: * Jun. 18, 2024

(54) COIN DISPLAY RACK

(71) Applicant: Yong Liu, Zhangzhou (CN)
(72) Inventor: Yong Liu, Zhangzhou (CN)
() Term: 15 Years
(21) Appl. No.: 29/928,110
(22) Filed: Feb. 8, 2024
(51) LOC (14) Cl. 06-04
(52) U.S. Cl. USPC D6/682.4

(58) Field of Classification Search

USPC D6/301, 672, 675, 675.1, 675.3, 675.4, D6/682, 682.2, 682.4; D3/304, 313; D19/91, 95

(57)

CLAIM

The ornamental design for a coin display rack, as shown and described.

DESCRIPTION

FIG. 1 is a perspective view of a coin display rack showing my new design;

FIG. 2 is a front view thereof;

FIG. 3 is a back view thereof;

FIG. 4 is a left view thereof;

FIG. 5 is a right view thereof;

FIG. 6 is a top plan view thereof; and,

FIG. 7 is bottom plan view thereof.

1 Claim, 7 Drawing Sheets
